BEET BLOCKING MACHINE

Hubert A. Schmitz, Ottawa, and Leo H. Worts-koetter, Glandorf, Ohio

Application May 22, 1939, Serial No. 275,048

3 Claims.

(Cl. 97—18)

This invention relates to an improved beet blocking machine.

One object of the invention is to provide a beet blocking machine which will be operated for effecting, mechanically, a hoeing operation, the invention having proven highly successful in use in hoeing beet fields.

Another object of the invention is to provide a machine of this character having hoes which may be guided in their travel so that a highly efficient hoeing operation will take place.

A further object of the invention is to provide a beet blocking machine which may be readily driven from the power take-off of a tractor.

As a further object, the invention seeks to provide a beet blocking machine which will simulate in operation the effective beet blocking, as done by hand.

And a still further object of the invention is to provide a machine of this type which will be capable of effecting beet blocking at a higher rate of speed than when done by hand.

Other and incidental objects of the invention not mentioned hereinbefore, will become apparent during the course of the following description.

Reference is now had to the drawings, wherein:

Figure 1 is a top plan view of our improved beet blocking machine.

Figure 2 is a side elevation of the machine, and

Figure 3 is a longitudinal sectional view on the line 3—3 of Figure 1 looking in the direction indicated by the arrows.

Reference is now had to the drawings with more particularity, wherein similar numerals of reference will be seen to designate like parts throughout the various views.

In said drawings, the numeral 1 indicates in general the frame of our improved beet blocking machine. The frame 1 includes front and rear rails 2 and 3 and side rails 4 and 5. In order to connect the machine to the hitch of a tractor, we provide a hitch shown generally as 6, having hitch bars 7 and 8. The hitch bars 7 and 8 have their corresponding inner ends connected to the opposite corresponding ends of the front rail 2. The forward or outer ends of the hitch bars 7 and 8 are connected to each other and to a hitch member 9.

The frame 1 has a central rail 10 which extends transversely of said frame and has its opposite ends connected to the mid portions of the side rails 4 and 5. It should be understood, at this point, that each of the rails of the frame and the hitch are of heavy inverted L-shaped

channel iron so that a rigid frame construction will be assured.

Mounted on the frame 1 and extending between the front rail 2 and the center rail 10, between the mid portion of the center rail and the side rail 4, is a supporting rail 11. A supporting rail 12, of similar construction, extends between the center rail 10 and the rear rail 3, between the mid portion of the rail 10 and the side rail 5. The rails 11 and 12 form supports for the corresponding inner ends of guide tracks 13 and 14. The guide track 13 extends from the side rail 4, medially between the front rail 2 and the center rail 10, to the supporting rail 11, while the guide track 14 extends from the side rail 5, medially between the rail 10 and the rear rail 3 to the mid portion of the supporting rail 12. As best seen in Figure 2 of the drawings, the rails 13 and 14 are each provided with overhanging flanges 15 which serve effectively to guide operating bars 16 and 17 which are slidably mounted in the tracks 13 and 14 respectively. The bars 16 and 17 are provided at their corresponding outer ends with openings 18.

Swingingly connected with the operating bars 16 and 17 are hoes 19 and 20. The hoes 19 and 20 each includes heads 21, having curved end portions 22 and connecting elements 23, which connecting elements are swingingly connected to the bars 16 and 17 at the openings 18. The other end portions of the connecting elements 23 are welded or otherwise suitably connected to the heads 21, said elements having extensions 24, the purpose of which will appear hereinafter. It should be understood that the hoe heads 21 are of suitable width to insure a wide cut. It has been found that, by providing the curved end portions 22, a more effective hoeing operation will be assured.

Mounted on the frame 1 are crank frames 25 and 26. As will be clearly seen in Figure 1 of the drawings, the crank frame 25 is located on the side rail 4 and extends from its mid portion to the front end thereof, while the crank frame 26 is located on the side rail 5 and extends from the center rail 10 to the rear rail 3. The frame 25 includes spaced arms 27, 28, 29 and 30. The arms 27 and 30, as best seen in Figure 3, extend laterally and upwardly and terminate in bearing plates 31. The arms 28 and 29 extend laterally and upwardly, in the same manner as the arms 27 and 30, and are also provided with bearing plates, it being understood that the lower corresponding ends of the arms 28 and 29 are secured to the side rail 4. It should be under-

stood that the arms 27 and 30 may be formed by extending the front rail 2 and the center rail 10. Bearings 32 are carried on the bearing plates 31 of each of the arms 27, 28, 29 and 30. Journaled by the bearings 32 is a crank shaft 33 having a crank 34, which is disposed to revolve between the arms 28 and 29. A connecting rod 35 connects the crank 34 with a loop 36 on the operating bar 16.

The frame 26 is of similar construction to the frame 25 and includes arms 37, 38, 39 and 40 which are secured to the side rail 5, like the arms 27 and 30. The arms 37 and 40 may be formed by extending the center rail and rear rail, respectively, upwardly and laterally. The arms 37, 38, 39 and 40 carry bearings 41 in longitudinal alinement, at their free upper ends. A crank shaft 42, of similar construction to the crank shaft 33, is journaled by the bearings 41. Said crank shaft 42 has a crank 43 on which is swingingly mounted a connecting rod 44, which has its opposite end swingingly mounted in a loop 45 on the operating bar 17. The crank 43 is mounted to revolve between the arms 38 and 39.

Mounted on the crank shaft 33 adjacent the outer edge of the arm 30 is a sprocket wheel 46. A sprocket wheel 47 is mounted adjacent the inner edge of the arm 37.

Mounted on the center rail 10 medially of its length is a standard 48 having a bearing 49 at its upper end. The standard 48 and bearing 49 are adapted to mount one end of a driving shaft 50 on which is mounted a double sprocket 51. Chains 52 and 53 connect, respectively, the sprockets 46 and 37 with the double sprocket 51. The opposite end of the shaft 50 is journaled by a bearing 54 which is carried on a pedestal 55, said pedestal being mounted on the front rail 2 medially of its width. A universal 56 is carried on the forward end of the shaft 50, forwardly of the front rail 2 and the pedestal 55, and is adapted for receiving thereabout a driving shaft from the tractor through suitable gearing mechanism.

In order to permit operators to guide the hoes 19 and 20, we provide seats 57 and 58 which are mounted, respectively, on the front and rear portions of the side rails 4 and 5. As will be observed, the seats 57 and 58 are located in alinement with the operating bars 16 and 17.

Swiveled wheels 59 and 60 are mounted in casters 61, located near the opposite end portions of the rear rail 3, said wheels supporting the machine at the rear end thereof. Wheels 62, which depend from the front rail 2 near the ends thereof, support the front end of the machine when it is at rest and not connected to a tractor or the like. Rests 63 are mounted on the rails 2, 3 and 10 and provide support for the feet of the operator when the machine is being moved from place to place.

The operation of the invention will now be described. The machine is connected to a tractor, by the hitch 6, and the power take-off of the tractor is connected with the universal 56. It should be understood that any other type of transmission may be employed for imparting movement to the driving shaft 50. After the machine has been moved to the beet field and placed in position for a hoeing operation, the hoes 19 and 20 are lowered into operative position. Operators will take their places at the seats 57 and 58 and will be in a position to guide

the hoes 19 and 20. In order to effect the guiding of the hoes, handles may be secured to the extensions 24 and have their opposite ends held by the operators. When the driving shaft 50 is caused to rotate, rotative movement will be imparted through the double sprocket 51, the chains 52 and 53, the crank shafts 33 and 42, to the connecting rods 35 and 44 which connecting rods will have their outer ends moving backward and forward, for effecting backward and forward movement of the operating bars 16 and 17. The operating bars 16 and 17 are, as heretofore explained, mounted to slide in the tracks 13 and 14. Backward and forward movement of the bars 16 and 17 will effect hoeing strokes for the hoes 19 and 20. These hoes will, of course, move laterally with respect to the longitudinal dimension of the machine. That is to say, the hoes will move transversely of the direction of the machine in motion. It has been found that, when the machine is in operation, under normal operating conditions, it travels about one-half to two-thirds of a mile per hour. At this speed, the hoes will make between thirty-five and fifty strokes a minute. With the hoes operating in this manner, the farmer is enabled to hoe his beets so closely that only a very few doubles remain. These doubles may easily be picked out as the machine moves along.

Our best blocking machine will operate satisfactorily in any type of soil. Its operation compares very favorably with hand blocking.

Having thus described the invention, what is claimed as new is:

1. In a beet blocking machine, a frame having front, rear and side rails, a center rail connecting the side rails, supporting rails, tracks carried between the supporting rails and the side rails, operating bars slidable in the tracks for reciprocatory movement therein, crank frames, crank shafts carried by the frames, connecting rods operatively connecting the crank shafts with the operating bars, hoes swivelly connected with the operating bars, a standard, a drive shaft carried by the standard, means for imparting rotative movement from the drive shaft to the crank shafts, and a universal carried by the drive shaft, the drive shaft being operable for rotating the crank shafts and shifting the operating bars whereby the hoes will be reciprocated in a plane at right angles to the longitudinal dimension of the first-mentioned frame.

2. In a beet blocking machine as recited in claim 1, wherein the hoes are provided with extensions adapted to be engaged for permitting swinging of the hoes during reciprocatory movement.

3. In a beet blocking machine, a frame having front and rear rails and side rails, supporting wheels carried by the frame, a center rail, tracks carried by the frame, supporting rails extending between the center rail and the front and rear rails, respectively, and supporting the corresponding inner ends of the tracks, operating bars slidably mounted in the tracks, hoes swivelly connected with the operating bars, and means carried by the frame and operatively connected with the operating bars and movable for imparting reciprocatory motion to the operating bars and hoes.
